UNITED STATES PATENT OFFICE.

EMANUEL ESCHELBACHER, OF NEW YORK, N. Y.

PETTICOAT.

1,074,109.

Specification of Letters Patent. Patented Sept. 30, 1913.

Application filed July 18, 1911. Serial No. 639,195.

To all whom it may concern:

Be it known that I, EMANUEL ESCHELBACHER, a citizen of the United States, residing in the city of New York, borough of 5 Manhattan, county and State of New York, have invented certain new and useful Improvements in Petticoats, of which the following is a full, clear, and exact specification.

10 This invention relates to petticoats and has for an object to provide an improved means for holding the waist-band portions securely in position and also provides fastening means.

15 In the drawing accompanying and forming a part of this specification, a view in perspective of the upper portion of the petticoat is illustrated.

In the garment herein illustrated there 20 is provided a flap portion 1, which may be considered as produced by forming two openings from the waist-band portion downwardly. The edges 2, of the flap will be so constructed as to overlie the sides 3, 25 of the main portion of the petticoat. In practice the flap 1 will be at the back, and the portion 4, which in the present illustration is the larger portion, will be at the front.

30 A belt 5, is shown secured to the flap. In the present illustration the belt is fastened to the central part of the waist-band portion of the flap. The belt 5 is provided with fastening devices 6, 7. This belt may in practice be made of elastic material and be provided with an adjusting device 8.

The waist-band portion of the flap is shown provided with a series of friction devices 9. These friction devices may be soft 40 rubber buttons provided with rough surfaces. The object of these friction devices is to prevent the back portion of the petticoat slipping down and to prevent the waist over which the petticoat is worn slipping up.

45 For affording a certain amount of adjustability so that the skirt may fit persons of different size waists, the edges 2, of the flap may in practice be constructed to be capable of extending a considerable distance over 50 the sides 3, of the main portion. Two plackets are thus provided. The main portion 4, is shown provided at the rear corners

of the waistband portion with securing devices 11, each of which will engage a selected member of a series of securing devices 12, 55 carried by the flap 1. The edges of the flap at the waistband are shown provided with securing devices 14, each of which will engage a selected member of a series of securing devices 15, carried by the waistband of 60 the main portion of the petticoat. The securing devices in both instances are illustrated in the form of hooks and eyes. Each placket thus has a double fastener. The edge of each side has a fastening device for 65 engaging any one of a series of fastening devices on the other side. This compound or reciprocal fastening will hold both edges of each side to the waist line and assure a trim appearance in whatever position of adjustment the parts may be caused to assume.

There has been but one form of embodiment of the invention illustrated, but it will be apparent that changes may be made within the scope of the claim. 75

Having thus described my invention I claim:

An adjustable petticoat comprising a main portion and a substantial flap portion, the flap portion being provided with an adjustable belt secured to the median portion of the waist band thereof, and adapted to encircle the body of the wearer to insure independent, uniform adjustment of the flap to the body of the wearer, said main and 80 flap portions being provided with coöperating fastenings on each side, whereby the sides of the main portion may overlap the belt beneath the flap portions and be independently adjusted and secured to the latter, 90 a portion of said belt contiguous to said flap portion, being provided on its inner surface with a plurality of friction members adapted to engage with the waist or other garment of the wearer when the belt is in adjusted position to prevent sagging or slipping of the petticoat. 95

In witness whereof I have hereunto set my hand in the presence of two subscribing witnesses.

EMANUEL ESCHELBACHER.
